The ornamental design for a fiber optic connector dust cap as shown and described.

DESCRIPTION

FIG. 1 is a top front left perspective view of one embodiment of a fiber optic connector dust cap showing my new design; FIG. 2 is a bottom front left perspective view thereof; FIG. 3 is a bottom rear left perspective view thereof; FIG. 4 is a left rear perspective view thereof; FIG. 5 is a left perspective view thereof; FIG. 6 is a right perspective view thereof; FIG. 7 is a rear elevational view thereof; FIG. 8 is a front elevational view thereof; FIG. 9 is a right side elevational view thereof; FIG. 10 is a left side elevational view thereof; FIG. 11 is a top plan view thereof; and, FIG. 12 is a bottom plan view thereof.

The dash-dash broken lines in the drawing depict portions of the fiber optic connector dust cap that form no part of the claimed design.

The dash-dot broken lines illustrate the bounds of the claimed design and form not part of the claimed design.
